schaft mit beschränkter Haftung, Berlin, Ger-
many, a corporation of Germany

Application September 1, 1938, Serial No. 228,068
In Germany September 25, 1937

4 Claims. (Cl. 177—329)

This invention relates to electric indicating means and more particularly to electromagnetically actuated rotary indicators for use in association with, for example, the instruments upon the dashboard of a vehicle such as an aircraft.

One of the objects of the present invention is to provide novel means for indicating when an electric current is flowing in an electric lead or flowing to an electrically actuated instrument.

Another object of the invention is to provide a novel indicator having a high sensitivity but capable of withstanding vibrations.

Another object is to provide a novel indicator having small dimensions.

A further object is to provide a novel electromagnetic device of the above character having a low magnetic leakage flux whereby adjacent instruments are safe from the disturbing effects caused by such leakage.

The above and further objects and novel features will more fully appear from the following detailed description when the same is read in connection with the accompanying drawing. It is to be expressly understood, however, that the drawings are for purposes of illustration only and are not intended as a definition of the limits of the invention, reference for this latter purpose being had to the appended claims.

In the drawing, wherein like reference characters refer to like parts throughout the several views:

Fig. 1 is a plan view, with a top cover removed, showing one embodiment of the present invention;

Fig. 2 is a side elevation in section taken substantially along line 2—2 of Figure 1;

Fig. 3 is a plan view of the above embodiment; and,

Fig. 4 is a section taken substantially along the line 4—4 of Figure 1.

The form of the invention illustrated in the accompanying drawing by way of example is an indicating device actuated by an electromagnet. The apparatus comprises a metallic core member which is surrounded by an exciter coil. An angularly shiftable armature is mounted upon said core adjacent suitable pole shoes which are associated with said core. The armature is coaxial with the coil and so arranged with respect to the core and pole shoes that the lines of force existing between the core, armature and pole shoes are substantially perpendicular to the coil axis.

In the form shown in Fig. 2, a cylindrical case 10 of a magnetic material is provided having

upon the upper edge 10a thereof, and formed integrally therewith, a pair of upwardly extending pole pieces 10b and 10c. Pole pieces 10b and 10c are diametrically opposed.

5 An exciter coil 11 lies flat upon and is attached to the bottom of case 10 and is connected in the circuit of an electric lead wherein it is desired to determine when a current is flowing.

From the bottom of case 10 a central core 12 extends above coil 11. The core is provided at the extremity thereof with a recess 12a for a non-magnetic bearing portion 13 in which there is rotatably supported a shaft 14 which is coaxial with said core. Upon a hub 15 which is mounted upon said shaft there is mounted a flat non-magnetic indicator portion 16 which supports above the coil 11 an armature 17. Indicator 16 is in the shape of a cross having four arms comprising sectors of circles. The indicator is to be 10 read in association with a face plate to be later described. Armature 17 is in the form of a flat ring portion having an inner annular flange 17a, and a pair of arms 17b and 17c extending outwardly from, and integral with, said ring portion. In order to increase the attraction between the pole pieces and the armature, arms 17b and 17c are provided at the outer edges thereof with flange portions 18 and 19, respectively, said portions being movable adjacent the pole pieces 10b and 10c. The flange portions 18 and 19 are tapered, i. e., they are in the shape of the outer surface of a sector of a cylinder formed between two intersecting planes which form an acute angle with one another. This flange formation makes it possible for a progressively increasing flange area to move adjacent each pole piece as the armature is angularly displaced from its initial position. Consequently, the motor action or the attraction by the pole pieces will correspondingly increase with the angular displacement of said armature.

In order that a suitable mounting may be provided for case 10, and also in order that a magnetic shield may be formed therefor, a cylindrical casing 20 is provided which surrounds said case and serves as a support for a face plate 21. Plate 21 is perforated at 22 (Fig. 3) such that the area removed corresponds approximately to the size and shape of the indicator portion 16. A central bore in said face plate serves as an upper bearing for the armature shaft 14.

In order that the angularly shiftable armature 17 may be yieldingly urged in a predetermined direction, a coil spring 23 is provided which surrounds shaft 14 and is attached at the extremities

thereof to hub 15 and bearing 13. When coil 11 is de-energized, spring 23 urges the armature against a limit-stop comprising an extremity 24a of a member 24. The member 24 is constituted by a strip of non-magnetic material which conforms to the curvature of the inner surface of container 10. Member 24 is rigidly held in place by means of a screw 25 (Fig. 1). An opposite extremity 24b of said strip serves as an abutment for a second limit-stop 26 for the armature 17 when said coil 11 is energized.

By permitting an actual contact between the armature 17 and a metal portion 26 of magnetic material constituting the second limit-stop and which is connected to the pole piece 10b by suitable means better shown in Fig. 4, a more positive magnetic attraction may be obtained which will further reduce the sensitiveness of the device to vibrations and to sudden shock. Such a metal portion 26 is mounted adjacent the extremity 24b of limit-stop 24 (Fig. 1). The armature is magnetically tightly gripped by portion 26 when the indicator is in the "on" position.

The visible portions of the indicator 16 are coated with a luminous substance, for example a phosphorescent paint or some radioactive material, in order to render these portions conspicuous.

In operation, coil 11 is energized by connection to a suitable energy source (not shown). Armature 17 is situated between the pole pieces 10b and 10c and the central core 12 in such a manner that the lines of force run substantially perpendicular to the axis of the electromagnetic device, i. e. the axis of coil 11 and core 12. The armature is attracted by said pole pieces and thus is angularly shifted against the pressure of spring 23 until flanges 18 and 19 are opposite the poles 10b and 10c, respectively, at which time the armature will engage the portion 26 of limit-stop 24b. The cross-shaped indicator 16 moves with the armature from the initial or "off" position, when the indicator arms are covered by plate 21, to the "on" position where said arms are visible through perforations 22.

There is thus provided a novel indicating device wherein the moving parts are angularly but not longitudinally shiftable. The apparatus therefore is not sensitive to the ordinary longitudinal vibrations which occur, for example, aboard aircraft. When the electromagnet is energized, the lines of force are required to bridge only very short gaps. Consequently, the stray or leakage flux is reduced to a minimum and the device will not electrically disturb such gauges, measuring apparatus and compasses, etc., which are located nearby. The indicator is of small size and is adapted to fit within a small bore which may be drilled in a dashboard or panel.

Although only one embodiment has been illustrated and described in detail, it is to be expressly understood that the invention is not limited thereto. For example, instead of employing the coil spring 23 to urge armature 17 in a counter-clockwise direction, a suitable draw spring or a permanent magnet arrangement may be used. Various changes may also be made in the design and arrangement of the parts without departing from the spirit and scope of the in-

vention as the same will now be understood by those skilled in the art. For a definition of the limits of the invention, reference will be had primarily to the appended claims.

5 What is claimed is:

1. In a signal device of the current indicator type, the combination with a pair of pole pieces, of a central core, a coil coaxial with said core, an armature having depending means on its outer periphery, non-magnetic means for mounting said armature for angular movement between zero and full scale positions on a shaft, said shaft being coaxial with and supported by said core, means comprising a limit-stop provided with ends defining contact surfaces for said armature whereby during angular movement thereof the armature contacts one of said surfaces in its zero position and the other of said surfaces at its full scale position, one contact surface only of said limit-stop means comprising a magnetic member, and means for yieldingly urging said armature against one surface of said limit-stop.

2. In a signal device a central core, an armature coaxial therewith, means supporting said armature upon said core for angular movement thereon between a zero and full scale position, an indicator member rigidly secured to said armature, and means comprising a substantially cylindrically-shaped limit-stop means provided with a plurality of ends defining a plurality of contact surfaces whereby one of said contact surfaces cooperates with said armature at its zero position and the other of said contact surfaces cooperates with said armature at its full scale position, the latter of said surfaces being provided with magnetic means.

3. In an instrument of the current indicator type, the combination with a pair of pole pieces, of a central core, a coil coaxial with said core, an armature insulated from and mounted for angular movement upon said core between a zero and full scale position, and means comprising a limit-stop provided with ends defining contact surfaces for said armature whereby during angular movement thereof the armature contacts one of said ends in its zero position and the other of said ends at its full scale position, one of said ends comprising a magnetic member connected with one of said pole pieces.

4. In an instrument of the current indicator type, the combination with a pair of pole pieces, of a central core, a coil coaxial with said core, an armature insulated from and mounted for angular movement upon said core between a zero and full scale position, said armature comprising a ring portion provided with depending flanges surrounding said core and outwardly extending arm members having tapered flanges at the outward ends thereof associated with said pole pieces, and means comprising a limit-stop provided with ends defining contact surfaces for said armature whereby during angular movement thereof the armature contacts one of said ends in its zero position and the other of said ends at its full scale position, one of said ends comprising a magnetic member secured with one of said pole pieces.
